UNITED STATES PATENT OFFICE

ARTHUR B. MODINE, OF RACINE, WISCONSIN, ASSIGNOR TO MODINE MANUFACTURING COMPANY, OF RACINE, WISCONSIN, A CORPORATION OF WISCONSIN

RADIATOR

Original application filed March 25, 1927, Serial No. 178,491. Divided and this application filed May 8, 1930. Serial No. 450,729.

My invention relates to heat exchange apparatus and has among its objects the production of an apparatus of the kind described which is convenient, compact, durable, efficient and satisfactory for use wherever found applicable.

A particular object of the invention is to provide improved radiators for heating dwellings, the device being particularly designed to induce a circulation of air through the radiator to thereby heat the air and discharge it in a heated condition into the room.

Another particular object of the invention is to provide an improved heating unit which may be positioned in a wall or floor of a room, or the like, and is constructed to induce a circulation of air into the room.

The invention also has as a particular object combining heat radiating fins with tubes through the latter of which the heating medium circulates and to arrange the heat radiating fins relatively to the tubes, so that circulation of air in the manner above referred to is accomplished.

The invention has these and other objects, all of which will be explained in detail and more readily understood when read in conjunction with the accompanying drawing which illustrates one embodiment which may be employed, it being obvious that changes and modifications may be resorted to without departing from the spirit of the appended claims forming a part hereof.

In the drawing, wherein like reference characters indicate like or corresponding parts:

Fig. 1 is a front elevation of a radiator embodying the invention;

Fig. 2 is a section taken on the line 2—2 of Fig. 1; and

Fig. 3 is a section taken on the line 3—3 of Fig. 1.

This application is a division of my application, filed March 25, 1927—Serial No. 178,491, which has now matured into Patent No. 1,851,720, granted March 29, 1932.

In the embodiment of the invention herein shown and described, the radiator or heat exchange device is generally identified by

the reference character 10 which includes a radiator unit generally designated 11. The radiator unit 11 preferably comprises a plurality of spaced headers or tanks 12 and 13 which communicate with each other through a plurality of tubes 14. In this embodiment of the invention, the tanks 12 and 13 are disposed substantially horizontal and the tubes 14 are disposed substantially vertical. The ends of the tubes 14 are secured in header plates 15 and 16, each of which is provided with flanges 17 which are soldered in grooves 18 formed in the header tanks 12 and 13.

The tubes 14 may be of any desired outline and are preferably of elongated cross section and are also preferably formed of relatively thin sheet metal. Heating fluid supply and return pipes 19 and 20 are provided for connecting the tanks 12 and 13 to the hot water or other heating system. A casing or housing 21 forms part of the radiator unit generally designated 10 and provides a passage 22, through which the passage of air is controlled through the medium of a damper 23.

The damper 23 is secured to a rod 24 which is journalled in opposite end walls 25 and 26 of the casing 21. The rod 24 of the damper is provided with a knob or handle 27 whereby the damper may be manually rotated to bring the damper into a plurality of adjusted positions.

The structure illustrated includes a plurality of sets of heat radiating fins 28 and 29 which are soldered or otherwise secured to the tubes 14 and extend transversely to the tubes 14 and longitudinally of the heat exchange device with one bank or set of fins arranged above another set or bank thereof. It will be noted that the plates or fins 28 and 29 are disposed substantially horizontal but are arranged in such a manner that the sides thereof form angles with the horizontal and the vertical, the arrangement being such that when heated fluid is delivered to the heat exchange device generally designated 10, and there is an exchange of heat through the walls of the tubes 14, air will pass diagonally upward

between the banks or sets of plates or fins 29 into the passage 25 and then, if the damper is in an open position, the heated air is directed diagonally upward between 5 the set or bank of fins 28 from which the heated air is discharged from the radiator into the room in which the radiator is located. It is manifest that the relatively cool air existing in the lower portion of the 10 room in which the heat exchange device is located will enter the casing 21 through the spaces provided between the plates or fins and tubes comprising the bank 29, be heated thereby during its passage therethrough, 15 and thence be guided by the casing 21 toward the set or banks of fins comprising the bank 28, through which the air previously heated by the tubes and banks of fins 29 passes and is thence discharged from the 20 passage 22 and into the room in which the device is located, thus providing means facilitating the circulation of the air while said air is being heated.

Having thus described the invention, what 25 I claim and desire to cover by Letters Patent is:

1. In a heat exchange device, the combination of a plurality of vertical spaced tubes, headers arranged at the opposite ends of 30 said tubes and providing means connecting said tubes, a casing extending from one header to the other, a plurality of spaced fins in contact with said tubes arranged transversely of said tubes and at an angle 35 to the vertical, said fins being arranged in sets, the fins of one set being disposed at an angle to the fins of another set and providing means for heating and inducing the directing of air into and out of said casing. 40 2. In a heat exchange device, the combination of a plurality of tubes arranged in spaced relation to each other and banks of fins in contact with said tubes arranged transversely of said tubes at an angle to a 45 plane transverse of the axis of said tubes and the fins of one bank being arranged at an angle to the fins of the other bank and said fins providing means for heating air and inducing said heated air to be conducted 50 in opposite directions.

3. In a heat exchange device, the combination of a plurality of tubes arranged in spaced relation to each other and banks of fins, the fins of one bank being arranged 55 at an angle to a plane transverse to the axis of said tubes and the fins of the other bank being disposed at an angle which is opposite to the angle of the first mentioned bank said fins providing heating means for inducing 60 and conducting air between said fins.

4. In a heat exchange device, the combination of a plurality of vertically arranged spaced tubes and a plurality of banks of transverse fins, said fins being arranged 65 in spaced relation and inclined to the ver-

tical and being inclined toward each other, and a casing extending from the outermost fin of one bank to the outermost fin of the other bank said fins providing heating means for inducing and conducting air between said fins. 70

5. Heat exchange apparatus comprising a tank, a second tank arranged above the first-mentioned tank, a plurality of tubes extending between said tanks and communicating therewith, said tanks being adapted to be connected in a heating system to supply heated fluid to said tubes, means forming a passage on one side of said tubes, means in contact with said tubes extending 75 between the tubes providing heated means for inducing a flow of air into one end of the passage, and means in contact with said tubes extending between the tubes for heating air and inducing a flow of air out of the 80 other end of said passage.

6. Heat exchange apparatus comprising a tank, a second tank arranged above the first-mentioned tank, a plurality of tubes extending between said tanks and communicating therewith, said tanks being adapted to be connected in a heating system to supply heated fluid to said tubes, means forming a 85 passage on one side of said tubes, means extending between the tubes for inducing a flow of air into one end of the passage, means extending between the tubes for inducing a flow of air out of the other end of said passage, and adjustable means for controlling the flow of air through said passage. 90

7. Heat exchange apparatus comprising a plurality of substantially vertically disposed tube sections adapted to have fluid circulated therethrough, fins secured to the lower ends of said tubes and extending from an end of said tube section toward the center of length of said tube section to induce a flow of air therebetween in one direction, and fins secured to the tube sections and extending from adjacent the center of length of said sections toward the opposite end of said sections to secure a flow of air therebetween in another direction, said fins providing heated means for inducing said air flow. 105

8. In a heat exchange device, the combination of a plurality of tubes arranged in spaced relation to each other and a plurality of banks of fins provided upon said plurality of tubes, the fins of one bank being arranged at an angle to the fins of the other bank and being in contact with said tubes and providing means for heating air and inducing said air to be conducted in opposite 110 directions relatively to said tubes, and said fins being inclined to a plane transverse to the axis of said tubes. 120

9. In a heat exchange device, the combination of a plurality of parallel heating 125

fluid conducting tubes and oppositely inclined spaced means associated with said tubes providing air passages arranged transverse of said tubes and being inclined to a plane transverse to the axis of said tubes and providing an element of means for heating air and inducing all of the air circulating between said spaced means of one portion of said tubes to be conducted in an opposite direction into contact with another portion of said tubes.

In witness whereof, I hereunto subscribe my name this 25th day of April, A. D., 1930.
